UNITED STATES PATENT OFFICE.

SAMUEL B. HYNES AND WILLIAM NEWTON BEST, OF LOS ANGELES,
CALIFORNIA.

RAILWAY-ROAD FURNACE.

SPECIFICATION forming part of Letters Patent No. 678,621, dated July 16, 1901.

Application filed March 14, 1900. Serial No. 8,682. (No model.)

To all whom it may concern:

Be it known that we, SAMUEL BURKE HYNES and WILLIAM NEWTON BEST, citizens of the United States, residing at Los Angeles, 5 in the county of Los Angeles and State of California, have invented a new and useful Railway-Road Furnace, of which the following is a specification.

One object of our invention is to provide a 10 furnace to be used along railway-tracks for various purposes—such, for instance, as exterminating weeds and grass or heating rails, bridge-irons, fish-plates, and other irons for the purpose of bending or straightening them.

Another object of our invention is to provide a railway-track furnace which can be used 15 at pleasure for exterminating the weeds and grass on the road-bed or the growth upon embankments, culverts, and bridge-approaches.

In order to conveniently eradicate the 20 growth along and at the sides of the road-bed, it is necessary that a large body of intense flame be projected upon the growth to be destroyed; and with this object in view our 25 railway-road furnace comprises a refractory reverberatory nozzle having a downwardly-extending passage terminating in a slot-shaped opening and one or more powerful hydrocarbon-burners, each located at the inlet end of the nozzle to supply the nozzle with 30 a large body of flame. The reverberatory-passage chamber of the nozzle is preferably tapered from the inlet toward the outlet end, so that the body of flame is gradually condensed as it approaches the outlet. The outlet 35 is preferably of a width to extend fully across the track and about a foot outside the rails, so that as the furnace when in operation is run along the railway the flame will 40 be positively directed against the growth between the rails and ties.

In carrying out our invention we prefer to 45 provide a fender extending from the outlet of the nozzle in the direction in which the flame is projected and at each side, so as to confine the flame to the track after it has left the nozzle, thus making the action of the fire more effective to destroy the weeds and grass. The fender also largely prevents the winds from 50 driving the flame to one side or the other. The fender is preferably in independent re-

movable sections and is arranged to be raised and lowered to accommodate different characters of growth. It is preferably formed in two side sections and a top section, each of 55 which is independently adjustable and removable. We also provide a removable guard below the nozzle, between the inlet and the outlet ends thereof, to shield the flame from the action of the air which would otherwise 60 tend to prevent the flame from reaching the ground effectively.

In order to use the apparatus for destroying the growth on the sides of embankments, the nozzles may be mounted on a turn-table 65 which is carried by the truck-frame of the furnace. The nozzle is preferably pivoted on an axle which lies in a horizontal plane, so that the outlet end of the nozzle may be raised and lowered to cause the flame to be 70 discharged horizontally or downwardly in an inclined plane at will. This swivel arrangement also enables the operator to turn the nozzle to throw the flame more to the windward side of the track in case the breeze is so strong 75 as to require this to be done in order to counteract the deflection of the flame. The side fenders are preferably supported by flexible connections in order to allow this deflection of the reverberatory nozzle while the fenders 80 are in operative position. In actual use with the fenders in place it is found that as the train runs forward the flame will extend rearwardly from the fenders about twenty feet and that in passing around curves it becomes 85 necessary to turn the nozzle slightly in the direction of the radius of the curve. One purpose of the swivel arrangement is to allow this to be done, so as to bring the flame to the required place for doing effective work 90 at the curve. When the curve has been passed, the operation will again bring the nozzle to a straight position relative to the body of the car.

The accompanying drawings illustrate our 95 invention.

Figure I is a side elevation of our invention as applied with a furnace-nozzle which is pivoted upon a horizontal axis. Fig. II is a plan of the same. Fig. III is a fragmental view of 100 the invention as applied with a turn-table. The nozzle is shown turned sidewise to di-

rect a body of flame down the sides of an embankment. The removable fenders are omitted from this view, for the reason that they will ordinarily be detached when the 5 nozzle is turned into the position shown in these views; but it is to be understood that the fenders will be attached for ordinary work along the road-bed and in cases where the deflection of the nozzle is not so great as to interfere with the fender. Fig. IV is a plan view of the appliance as shown in Fig. III. Fig. V is a section of the nozzle on line V V, Figs. III and IV, with the parts arranged to direct the flame outward through the axial 10 outlet. Fig. VI is a fragmental mid-section of the outlet end of the nozzle arranged to direct the flame at an angle from the axis of the nozzle-chamber. Fig. VII is a plan view showing the machine furnished with a turn-table with the parts in position for going 15 around a curve.

1 indicates a refractory nozzle having a downwardly-slanting passage-chamber 2, with an outlet 3 at the lower end and a burner 4, 20 located at the upper end of said passage, to supply the same with a body of flame.

Any number of burners may be used. One burner may be sufficient or more may be used, if required. In the drawings we have shown 25 two burners 4, and we have also shown the internal passage or chamber divided by a wall 5; but it is to be understood that the wall may be omitted or may be made sectional to allow the flame to pass from one side 30 to the other of the chamber or passage. We prefer to use the two burners and to employ the partition-wall 5, for the reason that the wall 5 gives strength to the refractory lining of the chamber. The furnace-nozzle is 35 preferably composed of a metal shell *a*, a fire-clay chamber-body *b* inside the shell, and a non-heat-conducting lining *c*, of asbestos or other suitable material, between the fire-clay chamber-body and the metal shell. A 40 very high heat is to be produced within the chamber, so that the chamber-body, which is preferably made of specially-molded fire-bricks, will become red or white hot, and the external metal shell *a* is necessary to hold the 45 chamber-body intact; and the asbestos filling or lining between the refractory chamber-body and the metal shell prevents the destructive heating of the shell, which would otherwise warp the same and injure the nozzle.

50 The nozzle-chamber passage 2 is preferably arranged slanting and tapering downward, and the burner or burners are of great capacity, so that the flame produced will reverberate within the chamber-passage 2 to intensely 55 heat the refractory walls thereof and produce an intense heat and flame which will issue from the outlet 3 under considerable pressure and will be projected forward and downward against the earth in such a way as to be most 60 effective for the destruction of growing grass and weeds. The extreme heat of the reverberatory chamber and the thorough commin-

gling of air and the vapors from the hydro-carbon by the reverberatory action causes a practically perfect combustion of all the oil 70 and prevents all loss from escape of unburned gases or smoke.

Our invention is not confined to the work of destroying vegetation along the road-bed, and when it is desired to heat surface-bent 75 rails or any ironwork which is required to be heated it is desirable that the nozzle may be adjusted to direct the flame upon the iron-work which is to be heated. For this purpose and for convenient adjustment when 80 not at work the nozzle is pivoted by trunnion-bearings 6 to a frame 7, carried by a truck 8.

9 indicates a quadrant-lever coöperating with the segmental rack 90 for holding the 85 nozzle at any desired inclination. The nozzle 1 is preferably of sufficient width to extend beyond the rails of the track and to allow the outlet 3, which is of a slot shape, to extend fully across the track. 90

10 indicates means for introducing a forced draft into the nozzle-chamber, so as to cause a large body of intense flame to issue from the slot-outlets 3 at a high pressure when this is desired. In the drawings the means for 95 producing a forced draft is indicated by the pipe 10, which leads from an air-compressor or fan. (Not shown.) We prefer to use a hydrocarbon-burner, although it is to be understood that any burner which may be found 100 suitable for the purpose may be used without departing from our invention. It is important, though, that the refractory chamber be filled with a body of flame, so that the chamber will be highly heated, thus to produce a high degree 105 of combustion of the oils and gases while passing through the chamber, so that the flame and heat emitted by the nozzle will be sufficient to destroy the green growth in a minimum period of time. 110

The heat that issues from the nozzle will be found highly effective for heating surface-bent railway-rails or bridge-irons, which are of considerable length and would otherwise be difficult to be properly heated unless taken 115 to the shop. The tapering form of the passage serves both to condense the flame and to produce the requisite pressure and also to direct the flame outward to the desired point.

It is desirable in some instances that the 120 flame shall be directed laterally of the track, so as to destroy the growth on the sides of embankments at bridge-approaches. For this purpose a turn-table 11, carried by the frame 7, Figs. III and IV, is provided, and 125 the refractory nozzle is pivotally mounted in said turn-table, so that the nozzle can be turned sidewise of the track, as indicated in said Figs. III and IV.

12 and 14 indicate the fender formed in 130 three sections, two side sections or fenders 12 being provided to extend along the sides of the path of the flame which issues from the outlet of the nozzle, and the top section or

fender 14 being arranged extending from the nozzle above the outlet of the nozzle. The side sections 12 of the fender protect the flame from the action of side drafts of air and concentrate the flame along the track. The top fender-section 14 prevents the flame from lifting from the ground, and thus causes the flame to act with the greatest efficiency upon the growth to be destroyed. Suitable means are provided for raising and lowering the fender. These means consist of flexible connections 15 for the side sections 12, respectively, which connections pass over pulleys 16, secured to the frame 7, and are operated by rods 17, one for each of the connections. Preferably a connection 15 is placed at each end of each of the side sections.

18 indicates connections fastened to the top fender 14 and connecting the same with crank-levers 19, which are operated by rods. The several rods 17 and 20 are carried to the platform 21 of the frame 7. These several rods are preferably provided with ratchet-teeth, as at 22, to catch upon a tie-rod 23, used between the two trusses 24 of the frame 7.

In Figs. V and VI the nozzle is shown with two outlets 3 and 31. The outlet 3 extends as an axial continuation of the chamber or passage 2. The outlet 31 is a downward extension of said chamber or passage. 32 indicates means for closing the outlet 3, and 33 indicates means for closing the outlet 31. So long as it is preferred to allow the flame to be emitted through the outlet 3 the closure 32 will be removed and the plug 33 will be inserted in the outlet 31 and fastened by the bolts 34, which pass through lugs 35, which project from the nozzle, and said bolts are secured by nuts 36. When it is desired to project the flame directly downward through the outlet 31, the closure 32 will be applied to close the outlet 3, and the plug 33 will be withdrawn from the outlet 31, so that the flame will be directed downward substantially at right angles to the axis of the nozzle-passage.

37 indicates an air deflector or fender arranged below the nozzle to protect the outlet end of the nozzle from the action of any air which would be forced under such end of the nozzle by the action of the forces when the nozzle is moved forward over the track. This deflector forces the air sidewise and prevents it from coming beneath and buoying up the flame which issues from the nozzle. When the apparatus is run over the track, the advance of the deflector 37 produces a partial vacuum underneath the front end of the nozzle, so that the flame can be effectively directed down on the growth to be destroyed.

38 indicates a lever for operating the air shield or deflector 37 to raise or lower the front end, as may be found desirable in the practical operation.

65 39 indicates a rod for operating the lever 38. In practical operation the apparatus will be drawn along the track in the direction of

the arrow, a supply of oil being provided in a tank which may be mounted on the frame 7, as indicated by the tank 40, or which may be the oil-tank of a supply oil-tank car. (Not shown.) The steam for the hydrocarbon-burner will be brought from the locomotive (not shown) through a hose 41. The air for forced draft may also be brought from the locomotive through the pipe 10, which opens into the inlet end of the refractory nozzle.

42 indicates the pipe through which oil is supplied to the burner.

When it is desired to heat railway-rails to straighten or bend them, the side fenders may be elevated out of the way or entirely removed. The rails and ties of the track will be covered with earth and the rails to be straightened or bent will be brought across the track in front of and as close to the outlet-nozzle as is requisite and the flame will be directed upon the rails to heat them. The same method is pursued in heating bridge-irons, fish-plates, or any other iron to be heated.

The speed at which the apparatus will be moved over the track will depend upon the intensity of the flame and upon the luxuriance of the growth to be destroyed. When it is desired to destroy growth on the sides of embankments or at bridge-approaches, the nozzle, mounted as shown in Figs. III and IV, may be swung around by turning the turn-table, and the flame may thus be directed to and down the sides of embankments or bridge-approaches.

When not in use and when coming to and from the work, the fenders are raised as high as possible and the outlet end of the furnace-nozzle is raised and the nozzle brought as near to a horizontal position as possible.

The opposite ends of the top fender 14 can be raised and lowered, respectively, at will, and the opposite ends of the side fenders 12 can also be raised independently, so as to allow the flame to find exit from the apparatus in a desired manner.

In case wind should deflect the blaze and cause it to be ineffective at the windward side of the track the swiveled nozzle (shown in Figs. III and IV) can be turned sufficiently upon the turn-table to cause the flame to be directed positively toward the windward side of the track, thus to counteract the effect of the wind. The flexible connections 15, which support the fenders, (not shown in Figs. III and IV, but which it is to be understood from Figs. I and II will be applied,) will allow the fenders to be deflected at the end of the nozzle, so as to carry the flame to the windward side of the track at the point where it issues from the nozzle.

What we claim, and desire to secure by Letters Patent of the United States, is—

1. A railway-road furnace comprising a truck; a downwardly-directed refractory reverberatory nozzle mounted aslant upon said truck and provided with a downwardly-slanting tapering passage which terminates at its

lower end in a slot-shaped outlet; and a hydrocarbon-burner located at the larger end of such passage to fill the passage with a body of flame.

5. 2. A railway-road furnace comprising a truck; a frame mounted on and extending beyond said truck; a tapering refractory reverberatory nozzle mounted aslant on said frame and furnished at its lower end with a narrow slot-shape outlet; a hydrocarbon-burner located at the larger end of said nozzle to fill the same with a body of flame; and a flame-fender extending beyond the nozzle-outlet.
- 15 3. A railway-road furnace comprising a truck; a frame mounted on said truck; a refractory reverberatory nozzle pivotally mounted aslant on said frame and furnished at its lower end with a slot-shape outlet; means for adjusting the slant of the nozzle; and a hydrocarbon-burner arranged to discharge flame into the inlet end of the nozzle.
4. A railway-road furnace comprising a truck; a frame mounted on said truck; a turn-table carried by said frame; a refractory reverberatory nozzle pivotally mounted on said turn-table; means for adjusting the inclination of said nozzle; and a hydrocarbon-burner arranged to discharge flame into the inlet end of such nozzle.
- 25 5. The combination of a truck; a frame carried by said truck; a refractory reverberatory nozzle pivotally mounted on the frame and furnished at its discharge end with a narrow slot-shape outlet; a hydrocarbon-burner arranged to discharge a body of flame into the nozzle; and a fender extending beyond the outlet of the nozzle.
- 35 6. The combination of a truck; a frame mounted on the truck; a refractory reverberatory nozzle pivotally mounted on the frame and furnished at its discharge end with a narrow slot-shape outlet; a hydrocarbon-burner arranged to discharge a body of flame into the inlet end of the nozzle; means for

adjusting the nozzle at different inclinations; a fender extending beyond the outlet of the nozzle; and means for adjusting said fender.

7. A railway-road furnace comprising a truck; a frame carried by said truck; a turn-table on the frame; a refractory reverberatory nozzle pivoted to the turn-table on a horizontal axis; means for adjusting said nozzle at different inclinations; a fender extending beyond the nozzle; means for raising and lowering the fender; and a hydrocarbon-burner to discharge flame into the inlet end of said nozzle.

8. In a railway-road furnace, the combination of a truck-carried frame; a refractory reverberatory nozzle mounted on such frame and furnished at its discharge end with a narrow slot-shape outlet; flame-fenders respectively at the sides of the nozzle-outlet; a flame-fender between the side fenders and above the plane of the nozzle-outlet; and means for adjusting the flame-fenders independently of each other.

9. In a railway-road furnace, the combination of a truck-carried frame; a refractory reverberatory nozzle mounted on such frame; flame-fender sections at the sides respectively of the outlet of said nozzle; a top flame-fender section between the side fenders and above the plane of the nozzle-outlet; crank-levers carried by the frame; connections connecting the opposite ends of the top fender with the crank-levers, respectively; operating-rods, one for each of said levers for operating the levers respectively; and means for raising and lowering the side fenders respectively.

In testimony whereof we have signed our names to this specification.

SAMUEL B. HYNES.

WILLIAM NEWTON BEST.
